UNITED STATES PATENT OFFICE.

WILLIAM J. KEYS, OF HUTCHINSON, KANSAS, ASSIGNOR TO THE CRAWFORD,
McGREGOR AND CANBY CO., OF DAYTON, OHIO, A CORPORATION OF OHIO.

GOLF-CLUB.

1,378,416.

Specification of Letters Patent.

Patented May 17, 1921.

Application filed October 29, 1919. Serial No. 334,359.

To all whom it may concern:

Be it known that I, WILLIAM J. KEYS, a citizen of the United States, residing at Hutchinson, in the county of Reno and State 5 of Kansas, have invented certain new and useful Improvements in Golf-Clubs, of which the following is a specification.

My invention relates to golf clubs and more particularly to an inserted striking 10 face and the means for securing such inserted body in the head of the club.

The object of the invention is to simplify the structure as well as the means and mode 15 of reinforcing the striking face of golf club heads, whereby they may not only be economically manufactured, but will be more efficient in use, afford long distance flight of the ball, and unlikely to get out of repair.

A further object of the invention is to 20 provide improved means for anchoring the inserted striking face whereby it will be not only less susceptible to the loosening influence of expansion and contraction, but will be held securely against the loosening 25 effect of the impact of the face upon the ball.

A further and important object of the invention is to provide means for securely embedding in the golf club head a body of ivory 30 arranged in such relation with the head as to utilize to best advantage the peculiar advantageous characteristics of this material, while minimizing the disadvantages thereof.

With the above primary and other incidental objects in view as will more fully appear in the specification, the invention consists of the features of construction, the parts and combinations thereof, and the mode of operation or their equivalents as 40 hereinafter described and set forth in the claims.

Referring to the drawings Figure 1 is a perspective view of the head of a golf club to which the present invention has been applied. Fig. 2 is a transverse sectional view substantially on line 2—2 of Fig. 1. Fig. 3 is a perspective of the insert body prior to its introduction into the club head.

Like parts are indicated by similar characters of reference throughout the several views.

The invention herein shown and described is particularly adapted for embodiment in drivers and brassies. In the drawings there 55 is shown a club of which 1 is the head, and

2 the usual handle shaft. It has long been the practice to provide the striking face 3 of the head 1 with an inserted body 4 of some material which will withstand the hard usage and repeated impaction or blows to 60 which a golf club is subjected, and which will at the same time afford a quick acting solid striking surface which will give "distance" to the ball. Ivory has been recognized as a desirable material so far as its 65 action upon the ball is concerned, but it possesses the disadvantage of a wide range of expansion and contraction under varying climatic and temperature conditions. As a result of the high factor of expansion and 70 contraction, various attempts to cement the insert body in the head 1 of the club have not been entirely successful. The contraction of the inserted body under such conditions causes it to be loosened in its seat or 75 socket and eventually entirely disengaged from the club. Moreover, it has been customary, due to economy of material or with the intent of affording a rigid impact surface from which the ball will rebound 80 quickly, to arrange the inserted ivory body with the grain thereof in line with the direction of the swing of the club, or perpendicular to the face 3 thereof, whereby the blow is received upon the end of the grain or 85 upon a cross sectional surface of the ivory.

There is at present a theory among the expert players, whether the same be true or not, that distance in the flight of the ball is attained not by a quick rebound of the 90 ball when engaged by the club, but by an action in which the club momentarily follows the ball in its initial flight, giving it the effect of a sudden push. Thus while a quick acting striking surface is highly 95 desirable or in other words, one which is not sluggish the effect upon the ball should not be too quick or too sudden, the action should be such that some portion of the momentum of the club is transferred to the 100 ball, thereby resulting in increased distance.

In the present construction, in lieu of the arrangement of the ivory insert, whereby the impact is received upon the end of the grain, the inserted body 4 is arranged with 105 the grain extending transversely to the line of impact, or parallel with the striking face 3, and also horizontal in relation with the head 1.

This arrangement of the ivory insert 4 110

in relation with the direction of its grain, involves two important functions, first the impact of the club upon the ball is received not axially or in line with the grain, but 5 transversely upon a longitudinal section of the ivory body. The tendency of the ball to rebound or "get away" too quickly and before receiving the momentum of the club is overcome, and the ball seems to stay with 10 the club until it receives the full force of the blow, and thus greater "distance" is attained. Second, the expansion and contraction of the ivory body under varying climatic and temperature conditions is least 15 in the direction of the grain and greatest in a direction transverse thereto, for this reason when the ivory body is arranged with the grain perpendicular to the striking face, the shrinkage of the inserted body is away 20 from the walls of the socket or recess in the head. Whereas arranged as shown in the drawing, with the ends of the grain contiguous to the walls of the socket or recess in which the body is inserted, there will be 25 but little shrinkage or loosening effect. The shrinkage or contraction of the body in this event will occur vertically in relation with the club head, and inasmuch as the insert intersects the top and bottom surfaces of 30 the head, such shrinkage is immaterial.

Moreover, the construction as illustrated in the drawing, enables the inserted body to be more accurately and closely fitted to the head. In preparing the head a recess or 35 cavity is bored in the striking face which recess is of circular form and of such size that the top and bottom of the recess intersect the top and bottom surfaces of the club head. Such a circular recess or pocket may 40 be conveniently and accurately formed with an ordinary auger-bit or may be turned in the head by mounting the head in a lathe or other suitable apparatus. The body to be inserted is turned from ivory stock 45 into a circular disk-like formation of proper thickness, and having a diameter substantially equal to that of the recess or socket. In turning the insert, it is shaped in such manner that the grain of the ivory 50 extends transversely across the flat face of the disk, the ends of the grain being exposed upon the periphery of the body. In locating the ivory insert in the head, the ends of the grain are brought into registry 55 with the sides of the recess or pocket by turning the insert to a position in which the grain extends horizontally or substantially parallel with the sole of the club. When so inserted the top and bottom of the 60 disk extend somewhat above the top and bottom surfaces of the club head as indicated by dotted lines in Fig. 1. This excess of material may be later removed and the insert contoured to agree with the contour 65 of the club head. The insert being engaged

in the club head upon those sides having the least factor of expansion and contraction, and the sides of the insert most susceptible to expansion and contraction under varying climatic and temperature conditions, being exposed much variation of the inserted body will have little or no effect. 70

To securely anchor the insert in the socket or recess, it is cemented by any suitable adhesive and in addition thereto there are provided in the ivory body one or more counter-bored holes 5 extending through the body from the front to the rear faces thereof. Seated within these counter-bored holes and engaging the head of the club are screws 6 75 the heads of which engage the internal shoulders or seats in the counter-bored holes 5. These screws serve to draw the inserted body into firm engagement with the bottom of the recess or socket and to anchor the insert in its adjusted position. The counter-bored holes 5 are screw threaded in their outer portions as at 7 and in such screw threaded portions are inserted screw threaded 80 plugs 8 also of ivory which not only conceal the attachment screws 6, but afford a continuous uninterrupted face. These screw threaded plugs are also preferably coated with an adhesive cement before being inserted in the screw threaded 85 holes 5. The screw threads serve to firmly anchor these plugs and to prevent disengagement, to take the shock and protect the adhesive cement from undue strain. It is obvious that in lieu of ivory plug 8 various 90 ornamental designs may be effected by providing plugs of different material and particularly of different color and arranging the holes 5 in various ornamental relations 95 or designs. 100

While ivory is the desirable material for inserts it is of course quite expensive and for other and cheaper varieties of clubs, various other materials may be used. For instance, lignumvitæ wood, ebony, or various other materials of fibrous character or possessing a grain may be employed in which case the grain is arranged transversely to the line of force and preferably horizontally or parallel with the sole of the 110 club in the manner heretofore described. Therefore while as before stated, ivory is the desirable material, it is to be understood that the present invention is not limited to ivory alone, but other materials when embedded in the same manner and arranged with the grain as before mentioned are to be considered as within the scope of the present invention. 115

From the above description it will be apparent that there is thus provided a device of the character described possessing the particular features of advantage before enumerated as desirable, but which obviously is susceptible of modification in its 120 130

form, proportions, detail construction and arrangement of parts without departing from the principle involved or sacrificing any of its advantages.

5 While in order to comply with the statute the invention has been described in language more or less specific as to structural features, it is to be understood that the invention is not limited to the specific 10 tails shown, but that the means and construction herein disclosed comprise but one of several modes of putting the invention into effect, and the invention is therefore claimed in any of its forms or modifications 15 within the legitimate and valid scope of the appended claims.

Having thus described my invention, I claim:

1. The combination with the head of a 20 golf club, of a body of ivory inserted in the striking face thereof, the grain of the ivory insert being arranged parallel with the face of the club.

2. The combination with the head of a 25 golf club of an ivory body inserted in the striking face thereof, the grain of the ivory body being arranged perpendicular to the direction of the impact of the body upon the ball.

30 3. The combination with the head of a golf club, of a body of ivory inserted in the striking face thereof, the grain of the ivory insert being disposed horizontally and transverse to the direction of impact 35 of the body upon the ball.

4. The combination with the head of a golf club of a body of ivory inserted in the striking face thereof and extending vertically from the top to the bottom thereof 40 and of less length than the striking face of the club, the grain of said body being extended longitudinally in relation with the striking face.

5. The combination with the wooden 45 head of a golf club of a fibrous body inserted in the striking face thereof, the head and inserted body being arranged with their directions of maximum and minimum expansion and contraction in substantially 50 parallel relation.

6. The combination with the wooden head of a golf club of a fibrous body inserted in the striking face thereof with the fibers of the club head and those of the in-

sert extending in the same direction where by the directions of maximum and minimum expansion and contraction of the head and insert will coincide.

7. The combination with a golf club head 55 of a body of ivory inserted in the striking face thereof, said body having a deeply counter-bored orifice, an attachment member positioned in the orifice of the inserted body and engaging the club head, said orifice being screw threaded and an ivory screw 60 threaded plug engaged in said orifice.

8. The combination with a golf club head 65 of an ivory body inserted in the striking face thereof, said body having a screw threaded orifice therein, an attachment member 70 for the inserted body introduced through said orifice into engagement with the club head and a screw threaded plug engaged in said orifice and covering the attachment member.

75 9. The combination of a golf club head and an inserted body embedded therein, extending from one face to the opposite face of the golf club head in the direction of greatest expansion and contraction of the 80 insert, the insert being overhung at its opposite ends by the head in the direction of least expansion and contraction of the insert.

10. The combination with a golf club 85 head, of an insert embedded in the striking face thereof, having counter-bored orifices therein, attachment members seated in said counter bored orifices and engaging the club head and plugs of material similar to 90 the insert fitted in said orifices over said attachment members.

11. The combination of a golf club head and an inserted body embedded therein, extending substantially from one face to the 95 opposite face of the head in the direction of the greatest expansion and contraction of the head, and overhung at its opposite ends by the head in the direction of least expansion and contraction of the head. 100

In testimony whereof I have hereunto set my hand this 3rd day of October, A. D. 1919.

WILLIAM J. KEYS.
